UNITED STATES PATENT OFFICE.

DAVID A. PROWS, OF CASTLEGATE, UTAH.

PENCIL-HOLDER.

1,157,580.

Specification of Letters Patent.

Patented Oct. 19, 1915.

Application filed May 4, 1915. Serial No. 25,747.

To all whom it may concern:

Be it known that I, DAVID A. PROWS, a citizen of the United States, residing at Castlegate, in the county of Carbon and State of Utah, have invented certain new and useful Improvements in Pencil Holders; and I do hereby declare the following to be a full, clear, and exact description of the invention, such as will enable others skilled in the art to which it appertains to make and use the same.

The invention relates to improvements in pencil holders.

The object of the present invention is to improve the construction of pencil holders, and to provide a simple, inexpensive and efficient pencil holder adapted to be readily applied to a pocket for holding the pencils contained therein and capable of being quickly attached to and readily removed from a pocket and of securely clamping a pencil or plurality of pencils and of preventing the same from accidentally falling out of the pocket.

A further object of the invention is to provide a pencil holder of this character which will present a neat and attractive appearance and which will not materially wear the inner or rear wall of the pocket.

With these and other objects in view the invention consists in the construction and novel combination and arrangement of parts hereinafter fully described, illustrated in the accompanying drawings and pointed out in the claims hereto appended, it being understood that various changes in the form, proportion and minor details of construction may be resorted to without departing from the spirit or sacrificing any of the advantages of the invention.

In the drawing Figure 1 is a perspective view of a pencil holder constructed in accordance with this invention, Fig. 2 is a front elevation of the same. Fig. 3 is a side elevation. Fig. 4 is a horizontal sectional view.

Like numerals of reference designate corresponding parts in all the figures of the drawing.

In the accompanying drawing in which is illustrated the preferred embodiment of the invention, 1 designates an approximately U-shaped body portion constructed of sheet metal or other suitable material and composed of inner and outer sides 2 and 3 and

a connecting top portion or bend 4. The outer portion or side 3 is preferably segmental but it may also be ornamented in any desired manner.

The device may be constructed of sheet material or made of precious metal and the body 1 is adapted to be hooked over the outer wall of a pocket with the bend 4 resting upon the upper edge thereof and the sides 2 and 3 at the inner and outer faces of the said outer wall of the pocket. The inner side or wall 2 is provided at its lower edge with spaced transversely aligned eyes 5 which receive pivots 6 of a clamping plate or lever 7 consisting of a substantially segmental body portion and teeth 8 extending from the body portion at right angles thereto adjacent to the plane of the pivots.

The teeth 8 extend inwardly and are adapted to be swung downwardly to the position illustrated in Fig. 3 of the drawing to enable the device to be readily placed over the outer wall of a pocket and when the device is placed in position on the said wall of the pocket the body portion of the locking plate or lever is swung downwardly to substantially a vertical position which carries the teeth or engaging portions 8 upwardly into engagement with the outer wall of the pocket at the inner face thereof and securely clamp the device to the pocket. By swinging the locking lever upwardly and downwardly the device may be readily fastened and unfastened and as the body portion of the locking lever is located in substantially the same plane as the inner side of the body member of the device it will be securely held in engagement or in its engaging position by the pencils when the same are placed in the device. Also its engagement with the inner face of the outer wall of the pocket will operate to hold it in its locked position so that there is no liability of its becoming accidentally unfastened.

The eyes 5 consists of strips or tongues bent upon themselves and secured by solder or any other suitable means and the pivots 6 may be formed integral with the plate or lever 7 or in any other suitable manner.

The U-shaped body member is provided at the inner side 2 with a narrow resilient pencil engaging strip 9 constructed of any suitable material and extending across the side 2 in spaced relation therewith and having terminal portions or arms 10 bent for

wardly or inwardly at substantially right angles and secured at their ends 11 to the inner side of the U-shaped body 1 in any suitable manner.

5 In Fig. 4 of the drawing the terminals of the narrow resilient pencil engaging strips are extended through slots 12 of the inner side 2 from the inner face thereof and are bent to form approximately hook-shaped terminals which engage the outer face of the said side 2, but solder or any other means may be employed in fastening the pencil engaging strips to the inner side of the body of the device. The pencil engaging strip is located within the pocket and the pencils are introduced between the strips and the inner side 2 of the body 1 and are securely held between the strip 9 and the side 2. The strip 9 through its resiliency 15 is adapted to accommodate itself to pencils of different sizes and in order to prevent the inner or rear wall of the pocket from being worn the strip 9 is provided with a covering 13 of suitable fabric such as plush, 20 which in addition to preventing the lining of the pocket from being worn is adapted to frictionally engage the pencils and assist in holding the same securely in the pocket. The pencils extending along the side 2 and 25 the plate or lever 7 are adapted to prevent the latter from swinging upwardly. Also the device will enable a pencil, fountain pen or the like to be readily introduced into and removed from it.

30 25 It will be seen that the pencil holder is exceedingly simple and inexpensive in construction, that it does not project from a pocket and presents a neat and attractive appearance. The device may be worn with-

out inconvenience to the wearer and it may 40 be ornamented in any desired manner.

What is claimed is:—

1. A pencil holder of the class described including an approximately U-shaped body adapted to straddle the outer wall of a 45 pocket, a locking lever mounted on the body at the inner side thereof, and arranged to be maintained in its position by the pencil, and means carried by the said body for holding pencils in the pocket. 50

2. A pencil holder including a substantially U-shaped body portion adapted to straddle the outer wall of a pocket, a locking lever pivoted to the inner side of the body and having engaging means extending inwardly toward the other side of the body for engaging the pocket, and pencil holding means carried by the inner side of the said body and arranged to hold a pencil against the said inner side and against the 55 locking lever. 60

3. A pencil holder including a substantially U-shaped body adapted to straddle the outer wall of a pocket, a locking lever pivotally connected with the inner wall at 65 the lower edge thereof and arranged to engage the pocket and a pencil engaging spring extending across the said inner side of the body above the locking lever and connected with the said body, said spring being 70 adapted to clamp pencils between it and the inner side of the body.

In testimony whereof I affix my signature in presence of two witnesses.
